UNITED STATES PATENT OFFICE.

FRANK B. ANGELL, OF SAN FRANCISCO, CALIFORNIA, ASSIGNOR OF SEVEN-SIXTEENTHS TO ALBERT KOENIG, OF SAN FRANCISCO, CALIFORNIA, AND ONE-EIGHTH TO CARL F. FORESTER, OF LOS ANGELES, CALIFORNIA.

CAN-OPENING DEVICE.

Application filed June 19, 1922. Serial No. 569,416.

To all whom it may concern:

Be it known that I, FRANK B. ANGELL, a citizen of the United States, residing at San Francisco, in the county of San Francisco and State of California, have invented new and useful Improvements in Can-Opening Devices, of which the following is a specification.

This invention relates to improvements in can openers, the principal object of which is to produce a can opener which will operate upon the side of a can in counter-distinction to the usual can opener which operated upon the top or end of the can.

Another object is to provide a can opener wherein the can being operated upon will be retained against turning.

A further object is to provide means whereby the cutter lever will be centrally held with respect to the vertical axis of the can.

Still further objects are to provide simple means for gripping the can, simple means for effecting the adjustment for any size of can and simple means for retaining the cutter in adjusted position with respect to the can.

Other objects and advantages will be apparent during the course of the following description.

In the accompanying drawings forming a part of this specification, and in which like numerals are employed to designate like parts throughout the same,

Figure 1 is a top plan view of my improved opener shown applied to a can.

Figure 2 is a cross-section taken on the line 2—2 of Figure 1 looking in the direction of the arrow,

Figure 3 is a vertical section taken on the line 3—3 of Figure 1 looking in the direction of the arrow,

Figure 4 is a vertical section taken on the line 4—4 of Figure 1, looking in the direction of the arrow, and

Figure 5 is a fragmentary detail view of the locking dog viewed from beneath the opener.

There are many commodities upon the market that cannot be removed from the can which is open on the end, that is by having a hole cut in one end. The reason is that the restricted size of the hole is not sufficient to provide for the size of the contents. This

is true in emptying canned meats and tamales from the can. An attempt has been made to provide a side seam which can be torn with a key, but this has proven unsatisfactory, owing to the tin out of which the can is made tearing.

I therefore provide a can opener which has a cutting knife which knife is adapted to penetrate the can and pass around the entire circumference of the can thereby severing one end of the can which will allow the entire contents to be removed without breaking or disfiguring.

In the accompanying drawings wherein for the purpose of illustration is shown a preferred embodiment of my invention, the numeral 6 represents the top of an ordinary can, and the numeral 7 the side wall of the same. This can is of the usual construction and needs no further description.

By now referring to Figure 1, it will be noted that the numeral 8 represents a bar provided midway of its length with teeth 9 and having at one end a V shaped member 11 which is equipped at its extremities with serrations 12 which are adapted to contact the side of the can at a point adjacent the end. This V shaped member is also provided with lugs 13 which are adapted to contact the end of the can as is shown in this figure. The member 11 is preferably secured to the bar 8 by rivets 14, but it is obvious that any means of connection might be used.

The opposite end of the bar 8 is provided with an offset portion 16, which offset portion engages a portion of a bar 17. The part of the bar 17 adjacent this engagement is dovetailed as is best shown in Figure 4 in order that the offset portion 16 may slidably engage the bar 17. This bar is provided

with a handle 18 at one end and at its opposite extremity with an offset portion 19 similar in construction to the offset portion 16 of the bar 8. This offset portion 19 engages the bar 8 as shown in Figure 3 and is also dovetailed to form a sliding engagement. At 21

I have shown teeth formed on the bar 17, and at 22 I have provided ratchet teeth, which ratchet teeth are adapted to be contacted by a dog 23. This dog is riveted or otherwise secured to a link 24, pivoted as at 26 to the bar 8 and provided with an operating knob 27. A handle 28 is pivoted to the bar 17 as shown at 29. The opposite extrem-

ity of this pivoted handle is arcuate and carries serrations 31, the purpose of which is to engage the side of the can in a manner similar to the serrations 12 when the handle 28 is moved in the direction of the arrow A of Figure 1.

By now referring to Figures 1 and 2, it will be noted that a pinion 32 is positioned between the bars 8 and 17 in such a manner 10 that its teeth engage the teeth 9 and 21 so that as the bars 8 and 17 are moved longitudinally relative to each other the pinion will roll therebetween. A bolt 33 passes through the center of the pinion 32 and has 15 pivoted upon its upper extremity a lever 34 offset as at 36 and terminating in a handle 37. A slider 38 is adapted to engage the teeth 41 formed upon the lever 34. This slider 38 carries a knife 42 upon its 20 under surface, which knife is of the ordinary construction. The numeral 43 designates a washer which is secured to the lower end of the bolt 33, which washer prevents the withdrawal of the pinion from its position 25 between the bars 8 and 17.

The operation of my device is as follows:—

The device as a whole is placed over the can so that the lugs 13 rest upon the top of 30 the can, which brings the serrated portions of the V shaped member 11 into contact with the side of the can. The knob 27 is then pressed with the thumb so as to disengage the dog 23 from the ratchet 22 after which 35 the bars 8 and 17 may be moved longitudinally relative to each other until the serrations 31 on the end of the handle 28 engage the opposite side of the can as best shown in Figure 1, after which the handles 40 18 and 28 are grasped in one hand so as to tend to move them together thus firmly gripping the can top. The slider 38 is then moved toward the can so that the knife 42 will contact the can. The handles 45 18 and 28 are then contracted so that the cutter 42 will pierce the side of the can as best shown in Figure 2. The tooth 39 on the slider will then automatically engage the teeth 41 as the handle 37 is moved in the direction of the arrow B. After a partial 50 cut has been made, the handles 28 and 18 are released and the can is partly rotated after which another cut is made. In this manner it is possible to cut around the entire 55 top of the can and sever the same without in any way mutilating the contents.

As before mentioned, I have provided means whereby the bolt 33 will always be positioned above the center of the can during the cutting action.

It is to be understood that the form of my invention herewith shown and described is to be taken as a preferred example of the same, and that various changes in the shape,

size and arrangement of parts may be resorted to without departing from the spirit of the invention or the scope of the subjoined claims.

Having thus described my invention, I claim:—

1. A device of the character described comprising spaced parallel bars, gripping means connected to said bars and adapted to engage the side wall of a can, a lever longitudinally movable between said bars, 75 and a cutting element slidably on said lever and adapted to be rotated about the side wall of a can, substantially as and for the purpose described.

2. A can opener comprising a pair of 80 longitudinally movable bars having teeth formed on the adjacent faces thereof, means for longitudinally moving said bars relative to each other, means for temporarily locking said bars against movement in one 85 direction, a pinion engaging the teeth on said bars, a lever pivoted to said pinion, and a cutting element slidably mounted on said lever, for the purpose specified.

3. A device of the character described 90 comprising a serrated bar, a V shaped member secured to one end of said bar, lugs formed on said member and adapted to contact the top of a can, a second bar having sliding engagement with said first mentioned 95 bar and having one of its faces serrated at pre-determined points throughout its length, means for temporarily locking said bars one to the other, a pivoted lever secured on said second mentioned bar and adapted to co-operate with said V shaped member for engaging the can, a pivoted cutting lever supported between said bars, and a cutting element slidably mounted on said pivoted cutting lever, for the purpose specified.

4. In a can opener, a V shaped member 100 adapted to engage one side of a can, a pivoted lever, one end of which is adapted to contact the opposite side of a can from said V shaped member, a bar secured to said V shaped member, a bar secured to said pivoted lever, means for maintaining a sliding engagement with said bars, means for temporarily locking said bars against movement in one direction, a pinion positioned between said bars and having rolling engagement with the opposing faces of said bars, a lever pivoted on said pinion, teeth formed on said lever, a slider movable longitudinally on said lever, a tooth formed 110 on said slider, said tooth being adapted to engage said teeth on said lever, and a cutter mounted below said slider and adapted to engage the side of a can at a point slightly 115 below its top.

In testimony whereof I affix my signature.

FRANK B. ANGELL.
